UNITED STATES PATENT OFFICE

OSCAR J. ELAM, OF MUSKEGON, MICHIGAN

HAIR-WAVING APPLIANCE

Application filed March 10, 1930. Serial No. 434,610.

This invention relates to a new and improved appliance for use in permanent hair waving, wherein a tress of hair is coiled about a rod and covered with absorbent material 5 impregnated with a hair treating solution, the whole being enclosed in a protecting tube adapted to be inserted in the cylindrical bore of an electric heater.

It is a common practice to employ a metal 10 foil or pasteboard protecting tube and to contract or crimp the inner end of said tube about the tress of hair, whereby the heated gases and steam are confined and prevented from passing through the inner or lower end 15 of the tube and against the scalp. These tubes are of a temporary nature and are destroyed after once being used, thus incurring considerable expense. Moreover, the method of closing or sealing the inner or 20 lower ends of these tubes about the tress of hair is not reliable or convenient.

The primary object of the present invention is to overcome the above objections by 25 providing an appliance including a vented rigid metal tube which may be repeatedly used, and means for readily and effectively closing the inner or lower end of said tube and for shielding the scalp from heated gases and steam.

30 A further object is to provide an appliance of the above kind which is simple in construction and capable of ready application to or removal from a tress of hair.

The invention consists in the novel form 35 and combination of parts hereinafter more fully described, shown in the accompanying drawing, and claimed.

In the drawing:

Figure 1 is a longitudinal sectional view 40 of the present appliance in use.

Figure 2 is a transverse section on line 2-2 of Figure 1.

Figure 3 is a plan view of the tube closure and scalp shield in open condition; and

45 Figure 4 is a perspective view of the tube.

Referring more in detail to the drawing, 5 indicates a tress of hair which is coiled about a rod 6 in the usual way, the whole being enclosed in a protecting tube 7 whose inner end 50 is closed about the tress of hair adjacent the

scalp by means of a shield —S—, and which is adapted to be inserted in the cylindrical bore of an electric heater shown by dotted lines at —H—.

In accordance with the present invention, 55 the tube 7 is rigid and formed of suitable metal, such as aluminum, the outer or upper end portion 7a of the tube being of conical form and provided with an axial restricted opening or vent 8 for the escape of excess steam or heated gases. The inner or lower end of the tube 7 is fully open and has its edge rolled outwardly to provide an external annular bead 9, further restricted openings 60 or vents 10 being provided in the sides of the tube adjacent its inner or lower end for the escape of excess steam or heated gases.

The inner or lower end of the tube 7 may 65 be readily closed about the tress of hair by means of the shield —S— which consists of a pair of similar arcuate sections 11 and 12 pivotally and frictionally secured together at adjacent ends and in overlapped relation by a rivet 13, said sections being formed of fibre or other heat insulating material. 70 When the shield sections are opened, they can be readily applied around or removed from the tress of hair adjacent the scalp, and they can be closed around the tress of hair as shown in Figures 1 and 2 to protect 75 the scalp from the heater —H— and the heated gases and steam escaping from the openings 10.

Means is provided for connecting the shield —S— to the lower or inner end of the 80 tube 7 so that such end of the tube will be maintained closed against the escape of heated gases and steam during the hair waving operation, when the shield sections are closed about the tress of hair. This means consists 85 of metal plates 14 and 15 riveted on the respective shield sections 11 and 12 centrally of their inner edge portions and having upwardly or outwardly projecting hooks 16 and 17 adapted to engage over the bead 9 on the 90 inner end of the tube 7, when the shield sections are closed. By applying the shield close to the scalp and thus connecting the tube 7 thereto, the heater —H— will be held 95 upright from the scalp.

From the above description, it will be seen that I have provided an appliance which may be readily and repeatedly used with uniform and efficient results, and which is quite simple in construction as well as inexpensive to use.

Minor changes may be made without departing from the spirit and scope of the invention as claimed.

10 What I claim as new is:

10 A permanent hair waving appliance comprising, in combination, a rigid cylindrical metal tube adapted to be inserted in the bore of a heater and having restricted vents respectively in its outer end and in its sides adjacent its inner end, the inner end of the tube being fully open and formed with an annular external bead, and a shield consisting of a pair of similar arcuate sections 15 formed of heat insulating material and having adjacent ends overlapped and frictionally pivoted together, and hooks carried by said sections so as to engage over the bead of the tube for connecting the shield to said tube in closing relation to the inner end of 20 the latter when the shield sections are closed about a tress of hair.

In testimony whereof I affix my signature.

OSCAR J. ELAM.
